(57) **CLAIM**

I claim the ornamental design for a drift anchor retrieval, as shown and described.

DESCRIPTION

FIG. 1 is a front elevation view of a drift anchor retrieval.
FIG. 2 is a left side view of a drift anchor retrieval.
FIG. 3 is a right side view of a drift anchor retrieval.
FIG. 4 is bottom view of a drift anchor retrieval.
FIG. 5 is a top view of a drift anchor retrieval.
FIG. 6 is a back view of a drift anchor retrieval.
FIG. 7 is a side view of a drift anchor retrieval disassembled for storage; and,
FIG. 8 is a perspective view of a drift anchor retrieval.
